CLAIM

The ornamental design for a stackable tray for containers, as shown and described.

DESCRIPTION

FIG. 1 is a side elevational view of the stackable tray for containers;

FIG. 2 is an opposite side elevational view thereof;

FIG. 3 is an end elevational view thereof;

FIG. 4 is an opposite end elevational view thereof;

FIG. 5 is a top isometric view thereof;

FIG. 6 is a bottom isometric view thereof;

FIG. 7 is a top plan view thereof; and,

FIG. 8 is a bottom plan view thereof.
